(57) **CLAIM**

I claim the ornamental design for a monocular, as shown and described.

DESCRIPTION

FIG. 1 is an upper perspective view of a first embodiment of the monocular in a first position;

FIG. 2 is a lower perspective view of the monocular shown in FIG. 1;

FIG. 3 is a front elevation view of the monocular shown in FIG. 1;

FIG. 4 is a left side view of the monocular shown in FIG. 1;

FIG. 5 is a rear elevation view of the monocular shown in FIG. 1;

FIG. 6 is a top plan view of the monocular shown in FIG. 1;

FIG. 7 is an upper perspective view of the monocular shown in FIG. 1 in a second position;

FIG. 8 is a front elevation view of the monocular shown in FIG. 7;

FIG. 9 is a left side view of the monocular shown in FIG. 7; and,

FIG. 10 is a top plan view of the monocular shown in FIG. 7.
